UNITED STATES PATENT OFFICE.

FREDERICK LANGHARST, OF EVANS CITY, PENNSYLVANIA.

REGISTER-OPERATING CAR-STEP.

949,299.

Specification of Letters Patent.

Patented Feb. 15, 1910.

Application filed July 2, 1909. Serial No. 505,710.

To all whom it may concern:

Be it known that I, FREDERICK LANGHARST, a citizen of the United States, residing at Evans City, in the county of Butler and State of Pennsylvania, have invented a new and useful Register-Operating Car-Step, of which the following is a specification.

This invention relates to car steps of that type designed to operate registers for indicating the number of persons entering the cars.

The object of the invention is to provide steps of this character which will only operate when a person is entering the car, the mechanism being such that when a person leaves the car by the same steps the recording mechanism will not be actuated.

A still further object is to provide mechanism of this type which will not operate a register unless more than one step receives the weight of a person entering the car.

Another object is to provide mechanism of this type which is simple and durable in construction and which can be readily applied to ordinary forms of cars.

With these and other objects in view the invention consists of certain novel details of construction and combinations of parts hereinafter more fully described and pointed out in the claims.

In the accompanying drawings the preferred form of the invention has been shown.

In said drawings:—Figure 1 is a front elevation of car steps embodying the present improvements, the adjacent operating mechanism being also shown. Fig. 2 is a vertical longitudinal section through the lower step and the adjoining mechanism, the upper step being shown in front elevation and with its protecting apron removed. Fig. 3 is a section on line A—B Fig. 1. Fig. 4 is a section on line C—D Fig. 1, a portion of the register being shown. Fig. 5 is a view, partly in elevation and partly in section, of a portion of the register and showing the actuating dog. Fig. 6 is a section through a portion of the register and showing the retaining pawl in elevation.

Referring to the figures by characters of reference 1, 1 designate hangers depending from the car structure 2, said hangers being connected by guide strips 3 and 4, disposed in stepped relation and each being provided with a central opening 5, while additional

openings 6 are located adjacent the corners thereof.

Arranged above the strips 3 and 4 are movable treads 7 and 8 respectively, each of these treads being provided near its corners with depending stems 9 movably mounted within the openings 6 in the strips 3 therebelow. Springs 10 extend around these stems and bear at their ends against the treads and the strips 3 respectively.

Extending downwardly from the middle portion of the tread 8 is a stem 11, provided at its lower end with a head 12 having its side faces converging downwardly toward each other to form an edge 13. Another stem 14 projects downwardly from the middle portion of the tread 7 and through the opening 5 in the strip 3 thereunder, this stem also terminating in a head 15, the side faces of which converge downwardly to form an edge 16. The two edges 13 and 16 are arranged out of alignment and are supported normally above projections 17 and 18 extending upwardly from a rock-bar 19. This rock-bar is supported at its ends in suitable brackets 20 and has an upwardly extending arm 21 which is pivotally connected to a pitman 22, extending loosely through one of the hangers 1. A coiled spring 23 is mounted on the pitman and bears at one end against the hanger 1, while its other end bears against one or more projections 24 on the pitman, this spring thus serving to hold the pitman normally in a predetermined position. The side faces of projections 18 converge upwardly to form edges which are normally close to and under the edges of the heads 12 and 15.

The pitman 22 is pivotally connected to an arm 25 having an eye 26 at one end and the opening in which is substantially semi-circular as shown at 27. This eye is mounted upon a rock-shaft 28 journaled within one or more hangers 29, that portion of the shaft located within the eye 26 being provided with a flat face as shown at 30. It will be apparent therefore that the arm 25 has a limited swinging movement upon the shaft 28, but that when the flat faces of the shaft 28 and the eye 26 come into contact the said shaft will be caused to move with the arm 25. Another arm 31 extends from the shafts 28, and is normally substantially horizontal, the free end of this arm normally resting upon a plate 34, which is suspended from the car

structure 2 by means of screw-threaded hangers 33. A rod 34 is pivotally connected to the arm 31 and a spring 35 extends around that portion of the rod immediately above the plate 32 and bears at one end against the arm 31 while its other end bears against a plate 36, which is loosely mounted on the rod 34 and which is slideable on the hangers 33, there being nuts 37 engaging said hangers and above the plate 36 whereby the said plate can be shifted for the purpose of increasing or diminishing the tension of the spring 35. The rod 34 extends upwardly into the car structure 2, and constitutes means for transmitting motion from the depressible step to a register located at any suitable point within the car. By referring to Figs. 4, 5 and 6, it will be seen that the register includes a casing 38 having a disk 39 mounted for rotation therein, there being ratchet teeth 40 upon one face of the disk and designed to be successively engaged by a spring-pressed dog 41 carried by the rod 34. A spring-pressed pawl 42 is mounted within the casing and back of the disk 39, and is designed to engage the teeth 40 so as to prevent return movement of the disk 39. The front face of the disk 39 is provided adjacent its periphery with numerals arranged in regular order and designed to be successively exposed through an opening 43 formed in the front of the casing. These numerals may range from 0 to 50 or from 0 to 100, and suitable mechanism of the usual or any preferred form may be utilized for transmitting motion from this disk to a second disk 44 on which hundreds may be indicated. Additional means of the usual or any preferred type may be provided for transmitting motion from disk 44 to a third disk 45 on which thousands are indicated. It is of course to be understood that each complete rotation of disk 39 is to produce a fraction of a complete rotation of disk 44, and that each complete rotation of disk 44 will produce a slight movement of the disk 45. Inasmuch as this mechanism is of an ordinary construction it is not deemed necessary to illustrate and describe the same in detail.

It is to be understood that the springs 10 hold the treads of the steps normally elevated to their greatest extent, and with the lower edges of the heads 15 and 12 above and out of contact with the upper edges of the projections 15 and 17. Spring 23 also holds the arm 25 normally pressed to one side, as indicated in full lines in Fig. 2, and the spring 35 exerts a constant downward pressure upon the arm 31 and rod 34. When a person entering the car places his weight upon the lower tread 7 said tread is depressed, and inasmuch as the edge 16 is arranged at one side of the edge on the projection 18, one of the beveled faces of the

head 15 will operate to swing the projection 18 laterally so as to bring the edge of the projection 17 under and past the lower edge of the head 12. This position has been indicated by dotted lines in Fig. 2. This rocking movement of the bar 19 will be merely sufficient to shift the arm 25 to the position shown by dotted lines in Fig. 2 and with the flat faces of the eye 26 and of the shaft 28 in contact. When the person then places his weight upon the next tread 8 the head 12 is forced downward against the projection 17 thereunder, and the beveled faces of said head and projection thus coöperate to complete the rocking movement of the bar 19. Arm 27 will thus be further shifted in the direction of the arrow in Fig. 2, this movement being sufficient to push the rod 34 upwardly such a distance as to cause the dog 41 to turn the disk 39 one tooth and to bring one of the characters on said disk into view through the opening 43 in the case 38. As soon as the weight of the person is removed from the upper tread 8 the various springs of the mechanism will return all of 90 the parts except the disk 39, to their initial positions.

Should a person desire to leave the car by the same steps, his weight is first applied to the upper tread 8, but inasmuch as the upper edge of the projection 17 is normally at the wrong side of the edge 13 of the head 12, it will be apparent that the downward movement of the said head 12 will tend to shift the pitman 22 so as to swing arm 25 in a direction the reverse of that indicated by the arrow in Fig. 2. Obviously therefore the register mechanism will not be operated.

As shown in Fig. 1, a supplemental stationary step 46 may be mounted on one of the hangers 1 so as to permit the conductor to enter or leave the car without operating the mechanism. Moreover, it is preferable to provide each of the treads 7 and 8 with a movable riser or apron 47, designed to close 110 the spaces below and in front of the treads.

It will be seen that mechanism such as herein described will accurately register the number of persons entering a car, and the same will be found especially advantageous, 115 because the same steps can be used both for ingress and egress, although the register mechanism will only be actuated by persons entering the car. Moreover, the said mechanism will not be operated unless a person 120 places his weight successively upon both steps of the car, and there is therefore no danger of the register being operated by persons standing upon the step.

Although the operating mechanism has 125 been shown dependent upon the successive pressure of two steps, it is to be understood that if preferred more than two steps may be utilized for this purpose. Moreover, by changing the relative positions of the rock 130

bar and the depressible actuating head, the mechanism can be caused to operate only when a person is leaving the car. The upper tread easily can be locked against movement in any desired manner so as to prevent the mechanism from actuating the register.

While the mechanism head is especially designed for use upon street cars and the like, it is to be understood that it can be utilized at the entrances to theaters, amusement parks, and other places, where it is desired to keep a record of the number of persons entering.

Various changes can of course be made in the construction and arrangement of the parts without departing from the spirit or sacrificing the advantages of the invention.

What is claimed is:

1. The combination with a register, and power transmitting mechanism connected thereto, of a rock bar, projections upstanding therefrom, yieldingly supported steps adjacent thereto, means extending from one of the steps for moving against one of the projections to shift the rock bar and bring the other projection into a predetermined position, and means extending from the other step and movable therewith for actuating the positioned projection to shift the rock bar and actuate the power transmitting mechanism.

2. The combination with a register, and means for transmitting motion thereto, of a rock bar having projections extending therefrom, yieldingly supported steps adjacent the bar, a stem projecting from one of the steps and movable against one of these projections to shift the bar and bring the other projection to a predetermined position, and a stem upon the other step and movable against the positioned projection to shift the rock bar and the motion transmitting mechanism.

3. In combination with a register, and mechanism for transmitting motion thereto, said mechanism including means for producing lost motion, of a rock bar, upstanding projections thereon, steps adjacent the bar, said steps being yieldingly supported, a deflecting head secured to and movable with one of the steps and against one of the projections to shift the bar and take up the lost motion in the motion transmitting mechanism, and a shifting head connected to the other step and movable against the other projection subsequent to the shifting of the rock bar to actuate the rock bar and mechanism and the register.

4. The combination with a register, and

mechanism for transmitting motion thereto, 60 said mechanism including means for producing lost motion, and a rock bar connected to said mechanism, upstanding projections on the rock bar, yieldingly supported steps, a deflecting head connected to one of the 65 said steps and movable against one of the projections to shift the bar and bring the other projection into a predetermined position, and a deflecting head connected to the other strip and movable against the positioned projection to shift the rock bar and 70 actuate the motion transmitting mechanism and the register.

5. The combination with register-operating mechanism, said mechanism including a 75 rocking member, and means for permitting lost motion, of a depressible yieldably supported step for shifting the rocking member and taking up the lost motion in the operating mechanism, and a second shiftable yieldingly supported step for actuating the rocking member and the balance of said mechanism.

6. The combination with a register and a reciprocating device for intermittently actuating the register, of a rock-shaft, means for transmitting motion therefrom to said reciprocating member, an arm mounted for partial rotation upon the rock-shaft, rocking elements having spaced projections 90 thereon, means for transmitting motion from said member to the arm, depressible car steps, means operated by one of the steps for engaging a projection on the rocking element to shift said element and move the 95 arm upon the rock shaft, said shifted element being brought into operative position, and a second depressible step for actuating said element while in operative position.

7. Mechanism of the class described including a rocking member, register-operating mechanism actuated thereby, said mechanism including means for producing lost motion, separately depressible car steps, and coöperating means movable with the steps 105 for shifting the rocking element to take up the lost motion and actuate the register mechanism, said means being ineffective except when actuated in a predetermined sequence.

In testimony that I claim the foregoing as my own, I have hereto affixed my signature in the presence of two witnesses.
